UNITED STATES PATENT OFFICE.

CHARLES D. ROGERS, OF PROVIDENCE, RHODE ISLAND.

MACHINE FOR MAKING SCREW-BLANKS.

SPECIFICATION forming part of Letters Patent No. 520,081, dated May 22, 1894.

Application filed February 15, 1892. Serial No. 421,575. (No model.)

To all whom it may concern:

Be it known that I, CHARLES D. ROGERS, a citizen of the United States, residing at Providence, in the county of Providence and State 5 of Rhode Island, have invented certain new and useful Improvements in Machines for Making Screw-Blanks; and I do hereby declare the following to be a full, clear, and exact description of the invention, such as will 10 enable others skilled in the art to which it app pertains to make and use the same, reference being had to the accompanying drawings, and to letters of reference marked thereon, which form a part of this specification.

15 The invention forming the subject of my present application for patent relates to machines for making wood-screw blanks, but more especially to such machines as are adapted to automatically produce at one operation from a continuous piece of wire cold-forged or swaged screw-blanks; the blanks thus produced having suitable points and heads, the latter having swaged slots or nicks formed therein to receive a driver-blade.

20 In United States Patent No. 386,091, granted to me July 10, 1888, I have shown and described a machine of the class just referred to; and in a later patent, No. 393,519, I have shown and described a novel die arranged to 25 simultaneously sever a headed blank from the standing wire and form a point thereon. In these patents the swaged screw-driver slots as drawn are closed, that is they do not extend entirely across the heads; it is obvious, 30 however, that by substituting suitably constructed dies and hammers blanks may be produced having open nicks.

In making swaged wood-screw blanks having open slots forged therein there is frequently produced at the slot-ends a slight waste of metal, and if the die and hammer work imperfectly such waste sometimes takes the form of adhering burrs or fins which must be removed by a subsequent operation.

35 The object I seek to attain is to provide machines for making swaged screw-blanks with a device arranged to remove adhering slot-burrs or fins from the blanks before the latter are dropped from the machine; that is 40 to say, such removal of the fins is effected simultaneously with the operation of forming the blanks.

To that end my invention consists, essentially, in the combination with suitably operating heading and cutting-off dies, of an intermittently movable clearer arranged to detach said fins after the slotted head has been forced from the die-cavity, as will be herein-after more fully set forth and claimed.

In the accompanying two sheets of drawings, 55 Figure 1, Sheet 1, is a longitudinal sectional view of a machine for making swaged screw-blanks provided with my improvements. Fig. 2, Sheet 2, is a partial plan view of the machine. Fig. 3 is an enlarged horizontal section 60 plan view of that portion of the machine employing the improvement, showing a headed piece of wire preparatory to being pointed and severed. Fig. 4 is a corresponding end view of the parts. Fig. 5 is an end view, showing the 65 clearer in the act of removing the slot-burr from the blank. Fig. 6 is a similar sectional view to Fig. 3, showing the cutting-off dies and clearer at the instant of completing their work. Fig. 7 is a corresponding end view. 70 Fig. 8 is a side elevation of the clearer and the corresponding half of the cutting-off die, mounted in a holder. Fig. 9 is a side elevation 75 of a swaged screw-blank, showing adhering slot-burrs or fins. Fig. 10 is a similar 80 view, with the burrs removed. Fig. 11 is an end view of the heading-die; and Fig. 12 is a transverse sectional view of it, taken on line $x-x$ of Fig. 11.

In the drawings I have indicated one form 85 of swaging machine well adapted to automatically produce wood screw-blanks from a coil or continuous piece of wire w by cold swaging. The free end of the wire or stock is advanced at intervals by any suitable feeding 90 device through a guide-tube w' and through the heading-die d ; a sufficient amount of wire, at the end of the feeding operation, then projecting beyond the die to completely 95 fill the die-cavity d' after the metal is upset therein. The heading is effected by an intermittently operated holder h (mounted in a reciprocating cross-head g) carrying say three hammers h', h^2, h^3 ; the face of the latter having a slot-forming tongue arranged to 100 engage a groove s' formed in the face of the die and communicating with the die-cavity. The hammers work successively upon the metal, thereby producing a screw-blank hav-

ing a head u^2 , an enlarged shank portion u^3 at the base of the head, and a swaged nick s , as in Fig. 10. Immediately succeeding the formation of the head the feeding mechanism 5 acts to force the headed wire from the die and advances it the distance required, after which oppositely located die-carriers o (Fig. 2) arranged to work transversely of the machine, operate simultaneously to sever the 10 blank from the wire. It will be seen that a holder i is secured to each carrier, the former being arranged to firmly retain the combined pointing and cutting-off die m . The adjacent ends or working faces of these dies (see 15 Figs. 3, 8, &c.) are sharpened and provided with a recess m' having inclined sides which act to sever the blank from the wire and at the same time form a point u' thereon; the die may also have a rounded groove m^2 20 formed at the end of the recess m' for the purpose of rounding off the end of the standing wire simultaneously with the blank-cutting operation, see Fig. 6. As the dies return to their normal position the heading-hammers next operate to upset the end of 25 the wire to produce another blank, as before described.

Now, it is known that sometimes the action of the slot-swaging mechanism produces outer fins or burrs f at the ends of the slots, see 30 Fig. 9, and in order to remove such waste metal I provide the inner adjacent ends of the holder i with clearer pieces b , e , adjustably secured thereto by screws e' . As drawn these 35 pieces have the form of knees and are let into the holders. The face e^2 of the piece e is adapted to engage the enlarged portion u^3 of the blank and serve as a support or rest therefor. The corresponding face, b^2 , of the other 40 piece or clearer b is cut away or recessed at b' to freely receive the head portion u^2 of the blank. When thus constructed it will be seen that the recess forms a U-shape in the 45 face of the clearer. The said face is set somewhat in advance of the face of the corresponding die (see Fig. 3), so that in use it will engage and detach the burrs f before the blank is fully severed. Fig. 5 shows the clearer pieces moving toward each other to engage 50 the blank, the recessed piece b being in the act of removing the burrs, and Figs. 6 and 7 show the relation of the several parts at the end of the operation; the burrs having been forcibly removed and the blank severed from 55 the wire w . Upon separating the dies m the

blank u drops from them completed, as indicated in Fig. 10, ready to be subjected to the action of thread-forming dies.

The mechanism may be so adjusted and timed that the clearer will engage the side of 60 the burrs and remove them in a lateral direction while the head of the blank is passing through the clearer, the latter at the same time moving transversely of the blank and being nearly at the end of its stroke. 65

I claim—

1. In a machine for making screw-blanks and swaging driver-slots therein, the combination, with feeding, swaging and cutting-off mechanisms, of an intermittently operating 70 clearer arranged and adapted to remove projecting slot-fins or burrs from the screw-blank before the latter is dropped from the machine, substantially as described.

2. In a machine for making screw-blanks 75 and swaging driver-slots therein, the combination, with feeding, swaging and cutting-off mechanisms, of a suitably mounted clearer, or fin-remover, having its working face arranged and adapted to engage and detach 80 projecting slot-fins or burrs from said blanks by the movement of the clearer alone or by the joint action of both the blank and clearer and means for intermittently operating the clearer, substantially as described. 85

3. In a machine for swaging screw-blanks, a heading die and hammers constructed to upset the metal to form a driver-slotted head, oppositely arranged cutting-off dies, intermittently operating feeding mechanism, and 90 a clearer moving in unison with the cutting-off dies arranged to remove slot-burrs from the blank while the latter is being severed from the wire or stock, substantially as described.

4. In a machine for swaging screw-blanks, 95 the combination, with feeding, swaging and cutting-off mechanisms, of two intermittently operating clearer pieces, one of which bears against and supports the projecting portion of the headed wire, and the other of which 100 has its working face arranged to engage with and detach projecting burrs or fins formed on the said headed portion of the wire, substantially as described.

In testimony whereof I have affixed my signature in presence of two witnesses.

CHARLES D. ROGERS.
